UNITED STATES PATENT OFFICE.

CHARLES A. COLBY, OF ST. JOSEPH, MISSOURI.

ATTACHMENT FOR WASHING-MACHINES.

No. 824,065.

Specification of Letters Patent.

Patented June 19, 1906.

Application filed August 14, 1905. Serial No. 274,102.

To all whom it may concern:

Be it known that I, CHARLES A. COLBY, a citizen of the United States of America, residing at St. Joseph, in the county of Buchanan and State of Missouri, have invented 5 certain new and useful Improvements in Attachments for Washing-Machines; and I do declare the following to be a full, clear, and exact description of the invention, such as 10 will enable others skilled in the art to which it appertains to make and use the same, reference being had to the accompanying drawings, and to the letters of reference marked thereon, which form a part of this specification. 15

The object of my device is to provide an attachment suited to operate washing-machines which are constructed with fly-wheels, and I accomplish my object by the mechanism 20 illustrated in the accompanying drawings, in which—

Figure 1 is a front elevation of my device attached to the fly-wheel of a machine. Fig. 2 is a side elevation of the same, and Fig. 3 is 25 a detail top view of a lever and a pitman broken away and duplicate plates connecting the same.

Similar letters refer to similar parts in the two views.

30 A is a washing-machine, and B a wheel similar to that commonly used with washing-machines operating with fly-wheels, said wheel having the ordinary connection with the usual interior mechanism of a machine.

35 C is a lever, and D a supporting-arm rigidly attached to the base or standards B' B' of the machine. Near the outer end and on the top of this arm there is a rigidly-fastened L-shape rod. The lower end of lever C is

40 provided with a hole with which said L-shape rod engages, the lever being thus carried pivotally. The lever is retained on said L-shape rod by the use of a pin or other convenient removable means.

45 H is a pitman carried at its wheel end upon

the outer end of a crank-pin h, the inner end of the pin engaging with a spoke of the wheel, the pin being provided at each end with the necessary washer and nut and the length of the rod being sufficient to allow the 50 spoke and end of said pitman, which are carried side by side, to have the necessary play. The outer end of the pitman is held spaced from the lever by plates I I, rigidly attached to the pitman upon opposite sides by bolts i i, 55 the other ends of said plates being carried on the lever by a pivot J. Said pitman may be attached to a spoke at any desired point; but to secure the highest speed it is preferably connected with the spoke of an ordinary 60 size washing-machine fly-wheel about three to four inches from the hub or center. The movement of this lever back and forth is so limited in distance that a machine with this attachment can be readily operated by a person 65 sitting as well as standing, and the speed that can be attained by the use of the attachment is such that laundering may be greatly accelerated.

What I claim, and desire to secure by Letters Patent, is—

In an attachment for a washing-machine provided with a fly-wheel, a supporting-arm rigidly attached on the lower part of the machine, an L-shape rod near the outer end of 75 said arm, a vertical lever its lower end carried pivotally on said rod, a reversing-arm, a crank-pin on said wheel carrying the inner end of said pitman, the duplicate plates rigidly fastened on the outer end of said pitman, 80 the outer ends of said plates having pivotal connection with said lever, and the washers, nuts, bolts and pin-fastenings substantially as shown and described.

In witness whereof I have hereunto set my 85 hand in presence of two witnesses.

CHARLES A. COLBY.
